Primary Examiner — Amy C Wierenga*Assistant Examiner* — Chariton Alexakis(74) *Attorney, Agent, or Firm* — Justin Lampel**CLAIM**

The ornamental design for a plate as shown and described.

DESCRIPTION

FIG. 1 is a perspective view of a plate showing the claimed design;

FIG. 2 is another perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof;

FIG. 8 is a bottom plan view thereof; and,

FIG. 9 depicts an enlarged detail view of portion 9 shown in FIG. 1.

The dot-dash broken lines in FIGS. 1 and 9, designating the boundary of the enlarged view, form no part of the claimed design.

1 Claim, 9 Drawing Sheets(56)
